UNITED STATES PATENT OFFICE.

DAVID APPLETON, OF LONDON, ENGLAND.

KNIFE-CLEANER.

SPECIFICATION forming part of Letters Patent No. 739,807, dated September 29, 1903.

Application filed May 8, 1903. Serial No. 156,191. (No model.)

To all whom it may concern:

Be it known that I, DAVID APPLETON, a citizen of the United States, residing at London, Middlesex county, England, have invented an

5 Improvement in Knife-Cleaners, of which the following description, in connection with the accompanying drawings, is a specification, like letters on the drawings representing like parts.

10 This invention has for its object the production of a novel, efficient, and durable knife-cleaner for cleaning simultaneously both sides of the knife-blade of any thickness.

15 My novel cleaner comprises flexible material to embrace the blade of the knife, suitable abrasive or cleaning material, and a back, pressure upon which is exerted through the flexible material onto the knife-blade.

20 Figure 1 in perspective shows a knife-cleaner embodying my invention, and Fig. 2 a section thereof in which the thickness of the knife-blade is greatly exaggerated.

25 In the drawings, A represents a piece of flexible material, which may be felt, cloth of any kind, or leather, and preferably the material will be in tubular form, as represented in Fig. 1. By making the flexible material as a tube the escape of cleansing-powders or cleaning material laterally from the flexible

30 material is obviated. Inside the flexible material I apply suitable abrasive or cleaning surfaces *a* *b*. These surfaces may and preferably will be of felt or other flexible material, with which is incorporated any usual

35 emery or other abrasive or polishing powder. These strips of felt may be glued or otherwise attached to the flexible tube A, and preferably the width of the strips *a* and *b* will be less than the width of the tube A when the 40 inner faces of the two strips contact with the knife-blade. Such construction enables spaces *c* to be left, in which may enter and settle any abrasive material that may be worked off from or out of the strips *a* *b*.

45 I have herein shown a back or presser as applied to both sides of the tube A, the presser B being represented as a hollow box, that it may receive emery or any other abrasive material *d*. The box has a suitable cover *d'*.

50 The upperside of the tube has a series of holes that register with holes in the upper strip *a*, and the emery or other abrasive material may

pass from said holes either onto the knife-blade or upon the upper surface of the strip *b*.

It will be understood that the strips *a* and *b* might be emery-cloth or any equivalent substance.

I have shown the back D, applied to the under half of the tube A, as a piece of wood.

The parts described may be made of any 60 size.

It will be obvious that the emery or other powder might be sprinkled throughout the length of the interior of the tube on the faces of the strips *a* and *b* and that in such event 65 instead of the hollow back B, I might use a solid back.

To use this device, the blade of a knife may be inserted between the two strips *a* *b*, and pressure exerted on either back B or D then 70 uppermost will cause the strips *a* and *b* to clamp the knife-blade with more or less force while the user, having the handle of the knife in his hand, moves the same longitudinally to effect the proper cleansing or polishing thereof. The backs or blocks B and D constitute 75 stiff bodies applied to the exterior of the flexible material or tube.

Having described my invention, what I claim, and desire to secure by Letters Patent, 80 is—

1. A knife-cleaner comprising a piece of flexible material folded upon itself and strips of flexible material supplied with abrasive or cleansing powder secured to the opposite surfaces of said folded material, and a stiff body attached to the exterior of the folded material. 85

2. A knife-cleaner comprising a flexible tube and strips of flexible material supplied with abrasive or cleansing powder, and an 90 attached stiff body at each face of the flattened tube.

3. A knife-cleaner comprising a flexible material having a series of holes, and a stiff body adapted to receive abrasive or cleansing material to enter said holes and contact with the 95 blade of a knife.

In testimony whereof I have signed my name to this specification in the presence of two subscribing witnesses.

DAVID APPLETON.
